TOOLHOLDER AND LOCK

Irving A. Elkins, Brooklyn, N. Y.

Application April 2, 1945, Serial No. 586,087

5 Claims. (Cl. 279—19.4)

1

This invention relates to safety holders or retaining means for use in connection with pneumatic devices, such as, chipping hammers, rivet-setters, etc.

Such pneumatic devices are each provided with a cylinder or barrel in which the rearward end of the tool is retained and some positive locking means should be provided for retaining the tool against its accidental withdrawal or dislodgement from the cylinder or barrel and thereby prevent possible accidents or annoyance. It sometimes happens that when one of these pneumatic devices is left around on the job with the operating tool in the pneumatically actuated device, a passer-by inadvertently brushes up against it or kicks it setting the device in operation and thereby causing the tool to escape from the barrel of the device and possibly injuring a person being present in the path of the escaping tool.

It is an object of the present invention to provide a holder or retainer for a tool employable in connection with a pneumatically-operated device, which will lock the tool to the device and thus prevent its escape or withdrawal therefrom during deliberate or accidental operation of the device.

A further object of the present invention is to provide holding or retaining means for a tool of the aforementioned type which will permit the tool being readily applied to the device to locked position or being readily unlocked and removed therefrom when desired.

It is another object of the present invention to provide a holder for pneumatically operated tools which will permit a rapid exchange of tools from the holder.

It is a still further object of the present invention to automatically lock such tool in position when inserted in the holder and with a slight turn of a sleeve member provided on the device by the hand to release the tool from the holder.

Further objects and advantages of the invention will appear from the following disclosure thereof together with the attached drawings which illustrate a certain form of embodiment thereof. This form is shown for the purpose of illustrating the invention since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

2

In the drawings:

Fig. 1 is a side-elevational view of the device made in accordance with the invention as applied to pneumatically-operated chipping hammer;

5 Fig. 2 is an enlarged view partly in section of the device showing the locking portion thereof with the tool in released position;

Fig. 3 is a view similar to Fig. 2 but showing the tool in clamped and operative position;

10 Fig. 4 is an end view seen in the direction of the arrow 4 of Fig. 2;

Fig. 5 is a sectional view seen in the direction of arrow 5 of Fig. 3;

15 Fig. 6 is a sectional view looking in the direction of the arrow 6 of Fig. 2;

Fig. 7 is a sectional view looking in the direction of the arrow 7 of Fig. 3;

Fig. 8 is a sectional view looking in the direction of the arrow 8 of Fig. 2;

20 Fig. 9 is a sectional view looking in the direction of the arrow 9 of Fig. 3;

Fig. 10 is a sectional view looking in the direction of the arrow 10 of Fig. 3, and

25 Fig. 11 is an end view looking in the direction of arrow 11 in Fig. 2.

In one of its general aspects, the tool retaining means comprises the housing 33 having at one end an opening for receiving a part of the tool-operating hammer 16 and at its other end an opening for receiving the rearward part of the tool 17 including the shoulder or flange 19, these openings being in communication, the resilient means 23 in the form of a helical spring disposed within the housing against which bears the annular member 22, the spring urging the member 22 in an outward direction. Disposed over the forward end of housing 33 is a sleeve 26 within which is disposed a spring 30 adapted to rotatably return the sleeve to initial position after being rotated, the housing 33 having elongated slots 25a formed therein in which are swingably arranged and movable therein the gripping or catch fingers or elements 25 having portions 24 projectable through the slots.

45 Cooperable cam means 38 on arms 25 and 39 in sleeve or shell 26 are provided for causing the projectable portions 24 being retracted and being released from the flange 19 when the sleeve 26 is rotated, this rotation of the sleeve and the retraction of the portions 24 permitting the annular member 22 being urged by the spring 23 into such a position as to maintain the portions 24 in retracted position, whereby the tool 17 may be withdrawn from the housing 33. A second

50 cam means 40 is formed in sleeve 26 for causing

55 cam means 40 is formed in sleeve 26 for causing

3

portions 24 to engage the tool flange 19 during return movement of the sleeve 26 to its initial position by the spring 30 upon depressing the annular member 22 by the tool flange 19 while the end portion of the tool is being inserted in the housing 33.

Referring now more particularly to the drawings, there is seen in Fig. 1 a pneumatically actuated hammer and tool 15 comprising the conventional hammer portion 16, chisel 17 and chisel holder and lock device 18. Chisel 17 is provided with an annular flange 19 having a straight surface 20 and a tapered surface 21.

When the tool 17 is inserted as shown in Fig. 3, its tapered surface 21 will abut against ring 22 which in the depressing operation will compress coil spring 23. Ring 22 as shown in Fig. 2 will maintain fingers 24 of arms 25 projecting through slots 25a in an outward position. Sleeve 26 is provided on its inside surface with a ridge 27 which at one point has the perforation 28 to receive the upturned end 29 of spring 30. The down-turned end 31 of spring 30 fits into a recess 32 of shank or housing 33 of the retaining and locking device 18. Spring 30 will have the tendency to rotate the cylindrical member 26 in the direction of arrow 34. Arms 25 are fulcrumed at one of their ends by means of pins 35 located within holes 36 of housing 33. The lower end 37 of arm 25 has a cam-like extension 38 which, when in disengagement with cam recess 39 of sleeve 26 will cause arm 25 to swing outwardly as shown in Fig. 2. Sleeve 26 has another set of cams 40 at its other end in the form of a rib with cutouts 41, each cut-out forming a cam surface 42, which when riding against the surface 43 of arm 25 will cause arm 25 to swing inwardly as shown in Fig. 3. When the arms 25 are in this position, their cam faces 38 are in engagement respectively with the recesses 39.

Arms 25 and sleeve 26, however, can swing and rotate respectively, only, when flange or collar 19 of drill 17 has pushed in annular member 22 from the position shown in Fig. 2 to the position shown in Fig. 3. Fingers 24 will thereupon, embrace the flat surface 20 of collar 19 holding the tool 17 securely within locking device 18. The movement of sleeve 26 is limited by the screws 45 secured to shank portion 33 of the device 18. The free end 46 of each screw 45 will project into slot 47 of housing 26.

The length of the slot 47 is slightly larger than the total rotative movement of sleeve 26 so that the cams may be operated.

Slots 48 of the screws 45 will receive when in their final position a spring 49, the free ends 50 of which enter a perforation 51 within shell 26, thus preventing screws 45 from loosening during vibration of the pneumatic hammer when in operation.

The device 18 is provided with screws 55 at the end 56 of shank 33 so as to permit securement of device 18 to sleeve 57 of the hammer 16. Since sleeve 57 may vary in size depending upon the size or type hammer employed, a sleeve 58 is provided to allow for such variations. Sleeve 58 is provided with holes 59 to clear screws 55. To assure alinement of holes 59 with screws 55, a projection, lip or tongue 60 is provided in sleeve 58, lip 60 fitting into a slot 61 of end 56 of shank 33.

Ring 22 and coil spring 23 are inserted within shank 33 through opening 62 and when placed are secured by means of washer 63 and snap ring 64.

4

When operating the device, tool 15 is usually held with its working end 17 in a downward direction. To release tool 17, for example, for the purpose of exchanging or replacing the same, 5 a slight turn of the sleeve 26 by the hand of the operator in the direction of the arrow 70 (Fig. 5), will cause cam 39 to push against extension 38 of arm 25 compelling or permitting arm 25 to swing outwardly as shown in Fig. 2. This outward movement of arm 25 is made possible, because sleeve 26 during its rotation has also brought the recess 41 in alinement with arm 25 as shown in Fig. 6, thus permitting arm 25 to swing outwardly. Coil spring 23 will press ring 22 into the position shown in Fig. 2, thus retaining arms 25 in outward extended position. Now 10 the tool 17 will be free from locking engagement with device 18, for withdrawal. When replacing a new tool, collar 19 thereof will press against ring 22 depressing the same into the position shown in Fig. 3, thus permitting spring 30 to rotate the sleeve 26 in the direction of arrow 34 causing cam surfaces 42 to strike against surfaces 43 of arms 25 moving the latter into the 15 position shown in Fig. 7, which is also the locking position seen in Fig. 3.

It is understood that tool-retaining means made in accordance with this invention may comprise a separate device attachable to a pneumatically actuated hammer or the retaining means may comprise portions, one or more of which may be made integral with or incorporated in the hammer and another portion of which is attachable to the hammer. It is evident that part of 20 the tool holding and locking means may be built into the hammer and part in a separate device attachable to the hammer.

Although the drawings, and the above specification disclose the best mode in which I have 25 contemplated embodying my invention, I desire in no way to be limited to the details of such disclosure, for in the further practical application of my invention many changes in the forms and proportions may be made as circumstances 30 require or experience suggests without departing from the spirit of the invention within the scope of the appended claims.

Having thus described my invention what I claim as new and desire to secure by Letters Patent, is:

1. Tool retaining means comprising in combination with a tool provided with a shoulder, a housing having at one end an opening for receiving a part of tool-operating means and at its other end an opening for receiving the said shoulder, said openings being in communication, resilient means within said housing, an annular member disposed within said housing adjacent said other end, said member bearing against said resilient means and being urged outwardly thereby, a rotatable sleeve disposed over said housing adjacent said other end thereof, a second resilient means, adapted to rotatably return said sleeve to initial position after being rotated, elongated slots formed in said housing, gripping elements swingably arranged at said slots and movable therein, said elements having portions projectable through said slots, respectively, cooperable cam means in said sleeve and on said elements, said cam means causing said projectable portions being retracted and being released from said tool shoulder when said sleeve is rotated, said rotation of said sleeve and said retraction of said projectable portions permitting said annular member being urged by said first-men-

tioned resilient means into such a position as to maintain said projectable portions in retracted position, whereby said tool may be withdrawn from said housing, and a second cam means in said sleeve, said second cam means causing said projectable portions to engage said tool shoulder during return movement of said sleeve to said initial position by said second resilient means upon depressing said annular member by said tool shoulder.

2. Tool retaining means comprising in combination with a tool provided with a shoulder, a housing having at one end an opening for receiving a part of tool-operating means and at its other end an opening for receiving the said shoulder, said openings being in communication, a helical spring within said housing, an annular member disposed within said housing adjacent said other end, said member bearing against said spring and being urged outwardly thereby, a rotatable sleeve disposed over said housing adjacent said other end thereof, spring means adapted to rotatably return said sleeve to initial position after being rotated, stop means for limiting extent of rotation of said sleeve, elongated slots formed in said housing, gripping elements swingably arranged at said slots and movable therein, said elements having portions projectable through said slots, respectively, cooperable cam means in said sleeve and on said elements, said cam means adapted to cause said projectable portions being retracted and being released from said tool shoulder when said sleeve is rotated in one direction, said rotation of said sleeve and said retraction of said projectable portions permitting said annular member being urged by said helical spring into such a position as to maintain said projectable portions in retracted position, whereby said tool may be withdrawn from said housing, and a second cam means in said sleeve, said second cam means causing said projectable portions to engage said tool shoulder during return movement of said sleeve to said initial position by said spring means upon depressing said annular member by said tool shoulder.

3. Tool retaining means comprising in combination a housing, resilient means within said housing, an annular member disposed within said housing adjacent one end thereof, said member bearing against said resilient means and being urged outwardly thereby, a rotatable sleeve disposed over said housing adjacent said one end thereof, a second resilient means adapted to rotatably return said sleeve to initial position after being rotated, elongated slots formed in said housing, gripping elements swingably arranged at said slots and movable therein, said elements having portions projectable through said slots, respectively, cooperable cam means in said sleeve and on said elements, said cam means causing said projectable portions being retracted when said sleeve is rotated, said rotation of said sleeve and said retraction of said projectable portions permitting said annular member being urged by said first-mentioned resilient means into such a position as to maintain said projectable portions in retracted position, and a second cam means in said sleeve, said second cam means causing said gripping elements to swing inwardly during return movement of said sleeve to said initial position by said second resilient means

upon said annular member being depressed against said first resilient means.

4. Tool retaining means comprising a housing having an opening at one end thereof for receiving an end portion of a tool having a shoulder, resilient means within said housing, an annular member disposed within said housing adjacent its said end, said member bearing against said resilient means and being urged outwardly thereby, a rotatable sleeve disposed over said housing adjacent its said end, a second resilient means adapted to rotatably return said sleeve to initial position after being rotated, stop means to limit the extent of rotation of said sleeve in either direction, elongated slots formed in said housing, gripping elements swingably arranged at said slots and movable therein, said elements having portions projectable through said slots, respectively, cooperable cam means in said sleeve and on said elements, said cam means causing said projectable portions being retracted and being released from said tool shoulder when said sleeve is rotated in one direction, said rotation of said sleeve and said retraction of said projectable portions permitting said annular member being urged by said first-mentioned resilient means into such a position as to maintain said projectable portions in retracted position, whereby said tool may be withdrawn from said housing, and a second cam means in said sleeve, said second cam means causing said projectable portions to engage said tool shoulder during return movement of said sleeve to said initial position by said second resilient means upon depressing said annular member by said tool shoulder.

5. Tool retaining means comprising a housing, a member disposed within said housing adjacent one end thereof, means in said housing urging said member in an outward direction, a rotatable sleeve arranged around said housing, means to rotatably return said sleeve to initial position after being rotated, openings in said housing, elements swingably arranged at said openings and having portions projectable through said openings, cooperable cam means in said sleeve and on said elements, said cam means adapted to cause said projectable portions being retracted when said sleeve is rotated, rotation of said sleeve and consequent retraction of said projectable portions permitting said member being urged by said first-named means into such a position as to maintain said projectable portions in retracted position, and a second cam means in said sleeve, said second cam means causing said elements to swing inwardly during return movement of said sleeve to said initial position, upon said member being depressed against said first-named means.
